UNITED STATES PATENT OFFICE.

WILLIAM C. SMITH, OF WARSAW, MISSOURI.

DESIGN FOR A HEATING-STOVE.

SPECIFICATION forming part of Design No. 16,370, dated November 3, 1885.

Application filed September 21, 1885. Serial No. 177,779. Term of patent 7 years.

To all whom it may concern:

Be it known that I, WILLIAM C. SMITH, a citizen of the United States, residing at Warsaw, in the county of Benton and State of Missouri, have invented and produced a new and original Design for Stoves, of which the following is a specification, reference being had to the accompanying drawings, forming part thereof.

- 10 Figure 1 is a side elevation of my newly-designed stove, and Fig. 2 a front elevation thereof with the foot-rest removed, these two views being deemed necessary to fully illustrate my design.
- 15 The leading feature of my design is an oval body or shell surrounded by a rectangular frame, from which columns extend upwardly at each side, surmounted by a top piece which is arched at each end.
- 20 In the drawings, A represents the shell or body of an ordinary oval or cylindric stove, the same being oval in vertical section, as shown. This body rests upon a base, B, extending from the rear to and beyond the front
- 25 of the stove, at which end the door *a* is located; and at the ends of the shell, rising upwardly from projecting ledges of the base at each side, are vertical columns *b*, on the tops of which rests a rectangular frame-piece, C,
- 30 up through which the upper side of the shell projects, as shown, corresponding columns, *b'*, being arranged intermediate of the said columns *b*, their bases being represented as resting upon a side casting, *e*, in the shape or
- 35 contour of a staircase leading upwardly therefrom. On top of the stove is a dome, D, sur-

mounted by any suitable figure, and at the front and rear of the shell, above the frame C, is an arch, *c*. The top edge of the door is of corresponding arch-like form, the two ends of which arch being represented as resting upon a vertical column, *e*, formed at each side of the door. The door is cast with a flat center or body, having its described parts in "relief," or raised outwardly therefrom. To one side 45 of the shell, extending slightly outward and lengthwise of the same, is a foot-rest, *m*; *o* representing the feet or legs arranged at convenient or proper points beneath the stove-base. The dome-base *p* in side elevation re- 50 sembles a series of square plates, one upon the other, and each upper one of less magnitude or dimensions than the one beneath, the same being cast hollow and in one piece. The said dome is concave between its sides, at each 55 end, by which to conform to the shape of the shell, the two sides appearing to rest upon the frame-piece C.

Having thus described the nature of my design, what I claim is—

The herein-described design for a stove, consisting of an oval body or shell surrounded by a rectangular frame, from which columns extend upwardly at each side, surmounted by a top piece which is arched at each end, sub- 55 stantially as shown and set forth.

In testimony whereof I affix my signature in presence of two witnesses.

WILLIAM C. SMITH.
